UNITED STATES PATENT OFFICE.

LEWIS G. BRADFORD, OF PLYMOUTH, MASSACHUSETTS.

IMPROVED APPARATUS FOR LEATHERING TACKS.

Specification forming part of Letters Patent No. 36,640, dated October 14, 1862.

To all whom it may concern:

Be it known that I, LEWIS G. BRADFORD, of Plymouth, in the county of Plymouth and State of Massachusetts, have invented certain new and useful Improvements in Machines for Leathering Tacks; and I do hereby declare that the following is a full, clear, and exact description of the same, reference being had to the accompanying drawings, forming a part of this specification, and in which—

Figure 1 represents a side view of the machine. Fig. 2 represents a top or plan view. Fig. 3 represents a front view. Fig. 4 represents a section on line A B of a portion of the front of the machine, and Fig. 5 represents two views of the tack-separator D detached.

My invention relates to the mode of separating the tacks and conveying them to the holding-dies or other receptacle, and the description will therefore be more particularly confined to this part of the machine.

In the drawings, A represents a hopper, into which the tacks are placed, and from which they descend into the slotted inclined guide B, the points of the tacks passing through the slot, while the heads are supported by the inclined sides of B.

The tacks are arrested at the bottom of the inclined guide B by a horizontal separator, D, having a notch, a, on its inner edge. The separator D rests and reciprocates on the stand C. To the stand C is pivoted a latch, b, having a groove, b', in which works a pin, c, projecting up from the separator D. To the outer end of D is fastened a vertical guide-arm, D', which projects sufficiently far beyond the stand C to receive the front end of lever E, which is pivoted at d, its rear end fitting into a cam-groove, d', in a pulley, F, on one end of shaft F'.

The operation is as follows: Tacks being placed in the hopper A descend down to the edge of the separator D, when, motion being communicated to shaft F' and pulley F, a reciprocating motion is imparted to the separator D by means of lever E, and said sep-

arator is drawn out to its extreme point of motion, as seen in red lines, Fig. 4. Its notch a is brought opposite the bottom end of the slot in the inclined guide B, thereby permitting one tack to slide into said notch, and which is separated from the other tacks and carried to the holding or other receptacle by the forward movement of the separator D, where it is thrown off or out of the notch a by the latch b, which is drawn inward for that purpose by the action of pin c in the cam-groove b', as indicated in black lines, Fig. 4.

By the backward motion of the separator its edge rubs against the side of the lowest tack, thereby causing it to assume a position which enables it to drop or slide readily into the notch a when in the proper position, as shown in red, Fig. 4.

As the receiving-dies and other parts of the machine may be of any known construction, it is not deemed necessary to describe the same, the invention relating solely to the mode of separating, conveying, and throwing off the tacks, and which operation has now been described.

Cam or groove d is so formed that the separator D rests for a short time at each extreme point of its motion.

What I claim as my invention, and desire to secure by Letters Patent, is—

1. The application and use of the horizontal reciprocating separator D, for taking the tacks singly from the foot of the inclined guide-plane and carrying them to the receiving-dies or other receptacle for holding the tack during the process of being driven through the leather or other material.

2. The combination, with the reciprocating separator D, of the self-acting latch b, for throwing or removing the tack from the notch a or its equivalent.

LEWIS G. BRADFORD.
